UNITED STATES PATENT OFFICE.

EMIL SUTHERLAND, OF POUGHKEEPSIE, NEW YORK, ASSIGNOR TO TWIN COUPLER COMPANY, INC., OF POUGHKEEPSIE, NEW YORK, A CORPORATION OF NEW YORK.

DESIGN FOR A POCKET LIGHTER.

Application filed September 4, 1928. Serial No. 28,041. Term of patent 3½ years.

To all whom it may concern:

Be it known that I, EMIL SUTHERLAND, a citizen of the United States, residing in Poughkeepsie, New York, have invented a new, original, and ornamental Design for a Pocket Lighter, of which the following is specification, reference being had to the accompanying drawing, forming part thereof, in which—

Fig. 1 represents a front elevation of the device.

Fig. 2 represents a rear elevation of the device.

Fig. 3 represents an end elevation of the device reading from right to left in Fig. 1.

Fig. 4 represents an end elevation reading from right to left in Fig. 2.

Fig. 5 represents a plan view of the device.

I claim—

The ornamental design for a pocket lighter as shown.

EMIL SUTHERLAND.
